DESIGN FOR A REARVIEW MIRROR FOR AUTOMOBILES

George C. Knight, Detroit, Mich.

Application April 25, 1946, Serial No. 128,956

Term of patent 7 years

(Cl. D14—6)

To all whom it may concern:

Be it known that I, George C. Knight, a citizen of the United States, residing, at Detroit, in the county of Wayne and State of Michigan, have invented a new, original, and ornamental Design for a Rearview Mirror for Automobiles, of which the following is a specification, reference being had to the accompanying drawings, forming a part thereof, and wherein:

Fig. 1 is a perspective view of a rearview mirror for automobiles showing my design; the dot and dash lines indicating a portion of an automobile being for illustrative purposes only.

Figs. 2 and 3 are respectively back and top elevational views thereof.

I claim:

The ornamental design for a rearview mirror for automobiles, as shown and described.

GEORGE C. KNIGHT.
